UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

DESK.

Application filed September 26, 1921. Serial No. 503,124.

To all whom it may concern:

Be it known that I, GEORGE P. WIGGINTON, a citizen of the United States, residing at the city and county of Kalamazoo, State 5 of Michigan, have invented certain new and useful Improvements in Desks, of which the following is a specification.

This invention relates to improvements in desks.

10 The main objects of this invention are:

First, to provide an improved desk especially adapted for use with machine book-keeping or accounting which requires the handling of loose sheets and the employment of a binder or file equipment for handling the sheets, and also statements or loose slips containing other data.

Second, to provide an improved desk of the character described which, when open, 20 fully exposes the accounting equipment which may be arranged therein in proper relation for convenient work.

Further objects, and objects relating to structural details, will definitely appear 25 from the detailed description to follow.

I accomplish the objects of my invention by the devices and means described in the following specification. The invention is clearly defined and pointed out in the 30 claims.

A structure which is a preferred embodiment of my invention is clearly illustrated in the accompanying drawing, forming a part of this specification, in which:

35 Fig. I is a front perspective view of a desk embodying the features of my invention with the top closed, a type-writing or accounting machine and sheet handling equipment with their supporting stands being shown in operative relation thereto.

40 Fig. II is a vertical central section from front to rear, with the top erected.

Fig. III is a vertical section corresponding to Fig. II with the top collapsed.

45 Fig. IV is an enlarged detail section on a line corresponding to line 4—4 of Fig. V showing details of the top support.

Fig. V is a detail vertical section on a line 5—5 of Figs. IV and VII showing 50 structural details.

Fig. VI is an end elevation of the top in erected position.

Fig. VII is a detail vertical section on a line corresponding to line 7—7 of Fig. V

showing details of the top supporting and 55 control mechanism.

Fig. VIII is a vertical longitudinal section of a desk embodying a modified form of my invention, the modification being in the top mechanism.

60 Fig. IX is a detail vertical section showing another modification or adaptation of my invention.

Fig. X is a front perspective view of a modified form of my invention in which the 65 top sections are arranged to fold instead of being arranged to slide and collapse to a vertical position as in the embodiments shown in Figs. I to IX.

Fig. XI is a front perspective view of the 70 desk shown in Fig. X with the top open.

In the drawing the sectional views are taken looking in the direction of the little arrows at the ends of the section lines and similar numerals of reference refer to similar parts throughout the several views.

75 Referring to the drawing, I provide a main frame comprising a back wall 1 and end walls 2 projecting forwardly from the back walls. These walls are braced by the 80 corner braces 3 which are arranged across the corners so as to leave the space between the walls unobstructed to receive a type-writing or accounting machine stand A indicated by dotted lines in Fig. I, and a 85 stand B, as is also indicated by dotted lines in Fig. I, to support accounting records.

I provide a top made up of a plurality of sections 4 connected edge to edge by hinges 5. These sections are of substantial 90 width, there being three sections in the structure illustrated forming a complete top for the desk as shown in the drawings. These top sections are provided with rollers 6 travelling in the angled ways 7 on the end 95 walls so that the top may be drawn forwardly to a substantially horizontal position as shown in Figs. I and II, or it may be collapsed to a vertical position as shown in Fig. III.

100 The rollers 6 are arranged in alignment with the hinges connecting the sections. The front top section is also provided with rollers towards its forward edge while the rear top section has rollers disposed near its rear edge as shown in Fig. VI. With the top thus supported the wide sections thereof are effectively guided in the ways

and swing around the angle thereof without binding.

The ends are provided with supports 8 upon which the front section rests when the 5 top is in its erected position. This relieves the rollers of undue strain when heavy books are laid upon the desk top or the user leans upon the same as is likely to occur.

Across the top at the rear is a top board 10 9 having a rib 10 along its edge so that inkwells, pencils and the like are retained thereon.

When the top is erected as shown in Fig. 15 II the rear top section swings against the under side of this shelf or top board, and when collapsed the front top section swings against the front edge thereof as shown in Fig. III.

An inner wall 11 is disposed in spaced 20 relation to the rear wall 1 providing a chamber into which the top is collapsed. To assist in handling the top and to equalize the same, that is, prevent its binding in the ways, I mount a rod or shaft 12 in 25 the bearings 13 at the rear of and adjacent the angle of the ways. On this rod are sprocket wheels 14, preferably fixed thereto so that they are rotated together. Sprocket chains 15 are secured to the rear 30 top section and passed over these sprocket wheels, the free ends of the chains being preferably provided with weights 16 (see Fig. II) so that the chains are kept taut and in effective engagement with the 35 sprocket wheels.

Coiled springs 17 are mounted on the rod with one end engaged with the sprocket wheels and the other with the counterbalance 40 18 so that when the top is collapsed these springs are placed under stress serving as a counterbalance and check for the top.

In the modification shown in Fig. VIII the pair of equalizing levers 19 are pivotally mounted on the back wall at 20 and connected to the ends of the chains or cables 21. These levers are connected by a pin and slot connection at 22. A spring 23 is connected to one of the levers so that the spring acts as a counterbalance and checking 50 means as in the embodiment described.

In Fig. IX the chains or cables 21 are connected directly to springs 24 which serve as counterbalance means. It is not, however, necessary to journal the rod as I have found that in practice the sprockets may be mounted to rotate upon the rod, the co-acting sprocket chains and springs serving as an effective equalizing means.

At one end of the desk I provide a drawer unit designated generally by the numeral 25. This unit is mounted on one end wall and has a supporting leg 26 at its inner end. This unit is spaced from the rear wall so that the top may be collapsed at the rear thereof, and its top 27 is spaced from the

main top so that the top 27 may be used for papers or the like and need not be disturbed when it is desired to erect the main top. The typewriting machine and record stands A and B are arranged in the space 70 between this drawer section and the opposite end of the desk and the top may be erected and collapsed without moving these stands, thereby rendering the desk especially adapted for accounting purposes. 75

In the modifications shown in Figs. X and XI the top sections 28 are hinged together at 29 so that they may be folded one upon the other, the rear section being hinged to the back wall at 30. This modification is 80 adapted to receive the accounting machine stand and record equipment the same as in the embodiments of Figs. I to IX but does not have the advantages of the sliding collapsible top. 85

I have illustrated and described my invention in several embodiments which I have found satisfactory. I have not attempted to describe other adaptations as I believe the disclosures made will enable 90 those skilled in the art to which my invention relates to adapt the same as may be desired.

Having thus described my invention, what I claim as new and desire to secure by 95 Letters Patent, is:—

1. The combination in a desk comprising a back wall and end walls extending forwardly therefrom, of a top comprising a plurality of sections hinged edge to edge, 100 angular ways on said end walls, rollers disposed at the ends of the top sections, the intermediate rollers being disposed in alignment with the hinges, the intermediate section being otherwise unsupported, a rod disposed at the rear of and adjacent the angles of said ways, sprocket wheels on said rod, sprocket chains running over said sprocket wheels and connected to the top, and coiled 105 springs mounted on said rod and engaged with said sprocket wheels so that the springs are placed under stress on the collapsing of the top.

2. The combination in a desk comprising a back wall and end walls extending forwardly therefrom, of a top comprising a plurality of sections hinged edge to edge, angular ways on said end walls, rollers for the top sections, a rod disposed at the rear of and adjacent the angles of said ways, 110 sprocket wheels on said rod, sprocket chains running over said sprocket wheels and connected to the top, and coiled springs mounted on said rod and engaged with said sprocket wheels so that the springs are placed under stress on the collapsing of the top. 115

3. The combination in a desk comprising a back wall and end walls extending forwardly therefrom, of a top comprising a 120

plurality of sections hinged edge to edge, angular ways on said end walls, rollers disposed at the ends of the top sections, the intermediate rollers being disposed in alignment with the hinges, the intermediate section being otherwise unsupported, a rod disposed at the rear of and adjacent the angles of said ways, sprocket wheels on said rod, and sprocket chains running over said sprocket wheels, and connected to the top. ¹⁰

In witness whereof, I have hereunto set my hand and seal.

GEORGE P. WIGGINTON. [L. S.]
